RAZOR BLADE SHARPENER

Saverio A. Spaziante, 8777 117 St., Richmond Hill, N.Y.

Filed Dec. 19, 1962, Ser. No. 72,905

Term of patent 7 years

(Cl. D37—1)

FIG. 1

FIG. 2

FIG. 3

FIG. 4

FIGURE 1 is a top plan view of a razor blade sharpener embodying my new design;

FIGURE 2 is a side elevational view thereof;

FIGURE 3 is an end elevational view of the same; and

FIGURE 4 is a bottom plan view of the same.

I claim:

The ornamental design for a razor blade sharpener, as shown.
